UNITED STATES PATENT OFFICE.

ARTHUR S. RICHARDSON AND JOHN H. J. COLCORD, OF DANVERS, MASSACHUSETTS, ASSIGNORS TO THE COLCORD-RICHARDSON COMPANY, OF SAME PLACE.

HOLDER FOR BARREL-CAPS.

SPECIFICATION forming part of Letters Patent No. 655,940, dated August 14, 1900.

Application filed August 29, 1899. Serial No. 728,845. (No model.)

To all whom it may concern:

Be it known that we, ARTHUR S. RICHARDSON and JOHN H. J. COLCORD, citizens of the United States, and residents of Danvers, 5 county of Essex, State of Massachusetts, have invented an Improvement in Holders for Barrel-Caps, of which the following description, in connection with the accompanying drawings, is a specification, like characters on the drawings representing like parts.

This invention relates to a holder for barrel caps or covers, which latter are usually made of burlap, canvas, or similar material; and the object of the invention is to provide an 15 improved appliance of this character which is simple in construction and capable of being manufactured at a low cost, and the device is of such a nature that it can be applied to and removed from the barrel with ease and 20 facility and when in position will firmly hold the cap or cover in place.

The device in the embodiment thereof illustrated in the accompanying drawings includes in its organization a split band, a 25 lever to which one end of the band is connected, and a member separate or free from the lever and serving to receive the fulcrum of said lever and connected to the other end of said band. In the present case the lever 30 is provided with a fulcrum constituting a part thereof, and the member to which reference has previously been made has one or more bearings to receive the fulcrum of the lever, so that said lever can be manipulated in such 35 a manner as to draw the band tightly around the upper end of the barrel, with the cap or cover between such parts.

In the drawings, Figure 1 is an elevation of the upper end of a barrel having a cap or 40 cover and provided with a holding device to maintain said cap in position. Fig. 2 is a horizontal sectional plan view of a portion of a barrel and the means employed for tightening the band. Fig. 3 is a detailed view showing a simple manner of connecting the band with one of the elements of the tightening mechanism, and Fig. 4 is a modification 45 showing a different kind of bearing member for the band-tightening lever.

50 In Fig. 1 I have shown a barrel B, the upper end of which is closed by a cap C, of bur-

lap, canvas, or such like, of substantially-circular form, the edge of the cap being drawn downward and being encircled by my improved holder to secure the same in place. 55 Said holder includes in its organization (see Figs. 1 and 2) a split band, as S, to one end of which the bearing member 12 is shown as connected. The bearing member 12 is represented as consisting of a longitudinal segmental plate the curvature of which agrees substantially with that of the barrel, as shown clearly in Fig. 2. The band S may be of any suitable material, such as galvanized wire, and what is represented as its right-hand end 60 in Figs. 1, 2, and 3 is shown as having a longitudinal loop 13, which fits flatwise against the right end of the segmental plate 12, said loop being held in place by lugs, as 14, 15, and 16, which can be punched from the stock or 65 body of the plate, the free ends of the lugs being turned over the side members and closed end of the loop, as clearly shown in Fig. 3, so as to hold the same tightly in place. The plate has extending from end to end thereof 70 the parallel walls or flanges 17 and 18, provided, respectively, with notches or recesses 75 19 and 20, which are in transverse alinement and which are adapted to receive the fulcrum of the band-tightening lever, hereinafter more 80 particularly described. It will therefore be seen upon inspection of Figs. 1, 2, and 3 that the split band S has connected to one end a bearing member having corrugated or toothed side members and that the spaces or notches 85 between the corrugations are adapted to receive the fulcrum of the band-tightening lever, and this lever is free or separate from the plate or member 12, so that any unusual slack that may be in the band may be taken 90 up by hand before the final tightening of the same by said hand-lever, as hereinafter described.

The take-up lever is denoted by 25, and it is of curved shape, it having at its working end 95 the oppositely-disposed projections 26 and 27, constituting a fulcrum device, and which are fixed to said lever. Said lever is also bifurcated, as at 28, and a pin or pivot 29 is disposed between the branches of the bifurcation at a point between the fulcrum device and the hand end of the lever. This pin or

pivot 29 is adapted to receive the loop or eye 30, which works between the branches of the bifurcation 28 and which is formed at what is shown as the left-hand end of the take-up lever 25. The parts being connected in the manner previously described, a cap will be drawn over the mouth or the upper open end of the barrel B and the split band S and its adjuncts will be drawn around the same, the take-up lever at this time being in its extreme retracted position, as shown by dotted line in Fig. 2, and the plate being against the cap C the slack will be taken up by drawing by hand on the lever, after which the oppositely-disposed projections 26 and 27, constituting the fulcrum of the lever, will be inserted in two alined notches 19 and 20 of the side pieces 17 and 18, respectively. After this the take-up lever will be pressed inward by hand in the direction shown by the arrow in Fig. 2, or until it is seated between the side walls or flanges of the bearing member 12, at which time the pivotal point 29 will have crossed a dead-center line passing through the axis of the take-up lever, whereby said take-up lever cannot be pulled outward by any stress upon the split band, and it will be understood that during the operation of the lever the left-hand end of the split band is drawn toward the opposite end thereof, so as to firmly bind the band in place around the cap. To remove the band, a finger can be inserted under the free end of the take-up lever and the same swung outward, so that the projections 26 and 27 can be taken from their bearings, which of course disconnects the lever and bearing member therefor. In some cases the bearing member can constitute a part of the split band, as represented in Fig. 4.

The split band S' (see Fig. 4) is shown as terminating in a longitudinal loop 12', the opposite longitudinal members or branches 17' of which are corrugated to form notches 19', and the fulcrum device 26' of the take-up lever 25' is adapted to be received between two alined notches upon the branches or side pieces of the bearing member or loop. The take-up lever 25' is connected with the left-hand end of the split band the same way as that shown in the previously-described figures, and the operation is also the same. From this it will be understood that our invention includes a split band having a bearing member at one end and a take-up lever separate from said bearing member and connected to the other end of the band, said bearing member being adapted to receive the fulcrum of said lever.

Upon reference to Figs. 1 and 2 it will be seen that one end of the split band S is corrugated, so that it is adapted to stretch in the direction of its length, and by reason of this feature said band can give as the take-up lever is crossing the dead-center, and as soon as this point is passed the wire will resume its initial position and will be tightly held in place.

It is evident, of course, that the holder can be used for many purposes other than securing barrel-caps in place.

Having described our invention, what we claim as new, and desire to secure by Letters Patent, is—

1. A device of the class specified, a split band provided at one end with a bearing member, the side pieces of which have a plurality of openings, and a take-up lever having a fulcrum adapted to be detachably fitted to alined openings in said side pieces, and the point of attachment of the free end of the band to the lever being movable across the dead-center line intersecting the axis of movement of said lever and the latter being arranged to lie between said side pieces, when in its clamping or effective position.

2. A device of the class specified, a split band provided at one end with a bearing member, the side pieces of which have a plurality of openings, and a take-up lever having a fulcrum adapted to be detachably fitted to alined openings in said side pieces, and the point of attachment of the free end of the band to the lever being movable across the dead-center line intersecting the axis of movement of said lever and the latter being arranged to lie between said side pieces, when in its clamping or effective position, said band having a corrugated portion.

3. A device of the class specified consisting of a curved bearing-plate having notched side walls, a band connected with said bearing-plate and having a loop in its free end, a lever adapted to be detachably fitted in alined notches in said bearing-plate and having a projection beyond said fulcrum to receive said loop, and arranged between said side walls when in its clamping or effective position.

In testimony whereof we have signed our names to this specification in the presence of two subscribing witnesses.

ARTHUR S. RICHARDSON.
JOHN H. J. COLCORD.
